(57) **CLAIM**

The ornamental design for a massager as shown and described.

DESCRIPTION

FIG. 1 is a perspective view of a massager according to an embodiment;

FIG. 2 is a front view of the massager of FIG. 1;

FIG. 3 is a rear view of the massager of FIG. 1;

FIG. 4 is a right side view of the massager of FIG. 1;

FIG. 5 is a left side view of the massager of FIG. 1;

FIG. 6 is a top view of the massager of FIG. 1; and,

FIG. 7 is a bottom view of the massager of FIG. 1.

The broken lines in the drawings are for the purpose of illustrating portions of the massager which form no part of the claimed design.

1 Claim, 4 Drawing Sheets
